UNITED STATES PATENT OFFICE.

JOHN JOHNSTON, OF NEW HAVEN, CONNECTICUT, ASSIGNOR TO WESTERN ELECTRIC COMPANY, INCORPORATED, OF NEW YORK, N. Y., A CORPORATION OF NEW YORK.

ELECTRICAL CONDUCTOR.

Application filed May 5, 1924. Serial No. 711,039.

This invention relates to electrical conductors and more particularly to the insulated electrical conductors of submarine cables.

- 5 It is an object of the invention to improve the insulation of such conductors both electrically and mechanically and to apply the insulating material to the conductor in such a manner as not to affect deleteriously 10 the conductor itself and in the case of a loaded conductor to apply the insulating material in such a manner that the loading material with which the conductor is wrapped will not be subjected to strains. 15 The use of hard rubber or semi-hard rubber as the material for insulating submarine conductors offers important advantages because of its low conductance, low dielectric constant, and the fact that it is 20 more rigid than soft rubber and its swelling by absorption of water is very limited. These advantages of hard rubber insulation for submarine cables are pointed out more in detail in a copending application of Williams et al., Serial No. 678,509 filed Dec. 4, 25 1923. On the other hand, it is very difficult if the rubber compound is vulcanized on the conductor to maintain an even thickness of insulation about the conductor during the 30 long vulcanizing process necessary and, furthermore, the action of the sulphur on the conductor is objectionable because of its progress during the long period of heating. Moreover, vulcanization of the rubber compound on the conductor cannot be accomplished satisfactorily in the case of a continuously loaded conductor of an improved 35 type recently developed. In this conductor, a recently discovered alloy is employed for the loading material, such alloy having a permeability at low magnetizing forces far in excess of that obtained with the best 40 grades of iron wire employed heretofore for continuous loading. For a more complete 45 description of this alloy and its characteristics reference is made to U. S. Patents No. 1,586,884, June 1, 1926, to G. W. Elmen, and No. 1,586,874, June 1, 1926, to O. E. Buckley. However, to obtain the best results 50 with this new alloy when used in submarine cables it is necessary to protect it from mechanical strains induced by hydrostatic pressure exerted on it when laid on the ocean floor and to protect against such 55 strains, it has been found desirable to im-
- pregnate the loaded conductor with an insulating compound such as liquid bitumen that fills all the interstices between adjacent turns of the loading material and between the loading material and the conductor, and, 60 in the case of a stranded conductor between individual strands of the conductor itself. To this end, it is preferable to employ an impregnating material which will flow at the temperatures and pressures encountered 65 in great depths of water as disclosed in a copending application of Archie R. Kemp Serial No. 617,511, filed Feb. 7, 1923. It is not satisfactory to vulcanize the rubber compound on a core of this type of conductor in 70 which a layer of liquid bitumen is provided under the insulating material, since the liquid bitumen mixes with the rubber compound during vulcanization and hardens to such an extent as to render it use- 75 less in protecting the loading material from subsequent strains.
- To provide an insulated conductor having the desired characteristics, the invention 80 contemplates the use of an insulating tape consisting of hard rubber or semi-hard rubber which is first vulcanized and then rendered sufficiently plastic to permit it being formed to fit the conductor and the seams jointed by means of heat and pressure. 85
- In the accompanying drawing, Fig. 1 is a view partly in section, of apparatus for heating and wrapping the tape about the conductor and then joining the seams by 90 passing through a suitable rolling mechanism; Fig. 2 is a sectional view taken along the line 2-2 of Fig. 1; Fig. 3 is a sectional view taken along the line 3-3 of Fig. 1, showing the construction of a die for forming the insulating tape into a suitable tube 95 surrounding the conductor; Fig. 4 is a sectional end view along the line 4-4 of Figure 1 of the rolling mechanism and Fig. 5 is a sectional view along line 5-5 of Figure 100 1 of a conductor insulated in accordance with this invention.
- Referring to the drawing, the conductor 105 6 and insulating tape 7 are passed at a predetermined speed through an oven 8 which is maintained at a constant temperature of approximately 150° C. by means of a gas heater 9 or other suitable means. As the conductor and tape pass through the die 10 the tape which is softened by the temperature of the oven is progressively fashioned 110

until it reaches substantially the shape shown in Fig. 3 of the drawing. As the insulated conductor emerges from the oven it is immediately passed between two 5 grooved rollers 11, 11 which are driven by suitable gears 12, 12. The outer surfaces of the rollers are grooved and the edges are brought together as shown so that a circular opening is provided therebetween having the 10 desired diameter for the insulated conductor, this opening being slightly smaller than the diameter of the conductor as it emerges from the die 10. The lower edges of the rollers are preferably shaped as shown 15 at 13 so that any excess insulating material is sheared off. While the rollers, as shown, are mounted a short distance from the oven, it is obvious that in practice they will be mounted sufficiently close so that there will 20 be no chance for cooling of the rubber compound before it passes between the rollers.

In order that the tape may be more easily rendered plastic as it passes through the oven, it is desirable to include in the rubber 25 compound a thermo-plastic material such as bitumen, preferably one of the harder varieties. While the condition of the insulating compound will obviously depend upon the 30 temperatures employed in the oven and the pressures maintained by the rollers, a compound which may be used at temperatures of 150° C. or somewhat less, consists of approximately 60% rubber, 20% sulphur and 20% bitumen. This compound is vulcanized 35 at temperatures corresponding to from 90 to 100 pounds steam pressure until the free sulphur content is reduced to .5% or less, in a manner such as is now commonly employed in the rubber industry. In place of, 40 or, in addition to, adding a bitumen to render the vulcanized compound more thermoplastic, it is possible to use in whole or in part the material made in accordance with the process described in a copending application 45 of Archie R. Kemp, which has issued as Patent 1,638,535 on August 9, 1927. This material in its preferred composition is composed of raw rubber compounded with 15% of sulphur by weight and it is thoroughly 50 mixed by working in a standard rubber mill. The term "hard rubber" as used in the specification and claims is intended to include also what is sometimes referred to as "semi-hard rubber" in which the sulphur content 55 may be as low as 15%.

What is claimed is:

1. The method of insulating a conductor which consists in vulcanizing insulating material, forming a tape of said insulating ma-

terial, applying said tape to closely surround 60 said conductor, and joining the edges of said tape to provide a continuous sheath of insulating material.

2. The method of insulating a conductor which consists in vulcanizing rubber, forming 65 a tape of said vulcanized rubber, applying said tape to closely surround the conductor, and joining the edges of said tape to provide a continuous sheath of insulating material. 70

3. The method of insulating a conductor which consists in vulcanizing insulating material, forming a tape, heating the vulcanized 75 tape, forming it while hot about the conductor, and joining the edges of the hot tape by the application of pressure to provide a continuous sheath of insulating material.

4. The method of insulating a conductor with insulating material which consists in 80 compounding rubber, sulphur and bitumen, vulcanizing said compound until the free sulphur content is reduced to .5% or less, heating the vulcanized material, forming it while hot about the conductor, and subjecting 85 it to pressure to provide a continuous sheath of insulating material.

5. The method of forming a continuous sheath of vulcanized hard rubber about a conductor, which method consists in vulcanizing 90 rubber, rendering plastic said rubber by adding bitumen, heating said conductor and a tape of said vulcanized rubber to a temperature of approximately 150° C., forming the tape about the conductor while 95 heated, and immediately thereafter applying to the conductor with the tape formed thereabout sufficient pressure to join the edges of the tape and press it into the desired shape. 100

6. The method of insulating a composite conducting core impregnated with fluid pressure equalizing means, which consists in forming a tape of vulcanized insulating material to closely surround said core, said 105 fluid pressure equalizing means being incapable when in contact with said insulating material of withstanding the temperatures required for vulcanizing said material for a sufficient time to permit vulcanization of the 110 tape in situ on said core, and joining the edges of said tape by the application of pressure to provide a continuous seamless sheath of insulating material. 115

In witness whereof, I hereunto subscribe my name this 2 day of May, A. D., 1924.

JOHN JOHNSTON.
